US0D1003088S

(12) **United States Design Patent** (10) **Patent No.:** **US D1,003,088 S**
(45) **Date of Patent:** **** Oct. 31, 2023**

(54) **SHELF**

(71) Applicant: **Guangzhou Jiaji Automotive Accessories Co., Ltd**, Guangzhou (CN)

(72) Inventor: **Junjie Wang**, Guangzhou (CN)

(73) Assignee: **Guangzhou Jiaji Automotive Accessories Co., Ltd**, Guangzhou (CN)

(**) Term: **15 Years**

(21) Appl. No.: **29/878,246**

(22) Filed: **Jun. 19, 2023**

(51) LOC (14) Cl. **06-04**

(52) U.S. Cl.

USPC **D6/675.1**

(58) **Field of Classification Search**

USPC .... D6/672, 673, 675, 675.1, 675.2, 675.3, D6/675.4, 675.5, 657, 660, 662, 662.1, D6/681, 681.1, 681.2, 683, 683.1, 706, D6/552, 512, 514, 525; D19/65, 75, 86 CPC A47F 5/0093; A47F 5/0081; A47F 5/0056; A47F 1/00; A47B 47/02; A47B 47/021; A47B 55/02; A47B 47/0058; A47B 88/41

(74) Attorney, Agent, or Firm — Nitin Kaushik

(57) **CLAIM**

The ornamental design for a shelf, as shown and described.

DESCRIPTION

FIG. 1 is a front perspective view of a shelf, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the shelf, shown in use with environment attached to the shelf;

FIG. 10 is a perspective view of the shelf, shown in an alternate state of use; and,

FIG. 11 is an enlarged detail view of area 11 in FIG. 2. The broken lines in the drawings illustrate the portions of the shelf, which form no part of the claimed design.

The dash-dot-dash broken lines encircling the enlarged views are for annotative purposes only and form no part of the claim thereof.

1 Claim, 11 Drawing Sheets
